(57) **CLAIM**

The ornamental design for a hair dryer, as shown and described.

DESCRIPTION

FIG. 1 is a perspective view of an embodiment of an hair dryer showing our new design.

FIG. 2 is a left side elevational view of the hair dryer of FIG. 1.

FIG. 3 is a right side elevational view of the hair dryer of FIG. 1.

FIG. 4 is a front elevational view of the hair dryer of FIG. 1.

FIG. 5 is a rear elevational view of the hair dryer of FIG. 1.

FIG. 6 is a top plan view of the hair dryer of FIG. 1; and, FIG. 7 is a bottom plan view of the hair dryer of FIG. 1.

The broken lines appearing in the figures are for the purpose of illustrating the environmental structure of the article of the claimed design and form no part of the claimed design.
